CATHARINE A. GRISWOLD, OF NEW YORK, N. Y.

DESIGN FOR THE ORNAMENTATION OF CORSETS.

SPECIFICATION forming part of Design No. 18,921, dated February 12, 1889.

Application filed January 4, 1889. Serial No. 295,475. Term of patent 14 years.

To all whom it may concern:

Be it known that I, CATHARINE A. GRISWOLD, of the city of New York, county and State of New York, and a citizen of the United States, have invented and produced a new and original Design for the Ornamentation of Corsets, of which the following is a full, clear, and exact description, reference being had to the accompanying drawing, forming part of this specification.

The single figure in the drawing represents a corset in side elevation containing my new design.

The leading and special feature of my new design consists in a band or stripe extending on the corset - surface from the lower edge thereof upwardly toward the waist-line, and thence with an edgewise bend upon itself returning downwardly to said lower edge, together with a band or stripe extending from the upper edge of the corset downwardly toward the waist-line, and thence with an edgewise bend upon itself returning upwardly to said upper edge, the bent portions of said respective bands or stripes being located opposingly to each other below and above the waist-line of the corset, and a circular band or stripe located at the said waist-line between the opposed bent portions of the bands or stripes, extending upwardly and downwardly from the corset-edges.

A represents a corset, which may be in the usual and ordinary form.

B represents a band or stripe extending from the lower edge of the corset upwardly toward the waist-line thereof, and thence with an edgewise bend, b, upon itself returning downwardly to said lower edge.

B' represents a band or stripe extending from the upper edge of the corset downwardly toward the waist-line thereof, and thence with an edgewise bend, b', upon itself returning upwardly to said upper edge.

The bent portions b and b' of the respective bands B and B' are located opposingly to each other on the corset, above and below the waist-line thereof.

C represents a circular band or stripe, which is located at the waist-line of the corset and between the opposed bent portions b and b' of the respective bands or stripes B and B'.

What I claim is—

The design for the ornamentation of a corset herein described and shown, the same consisting in a band or stripe, B, extending on the corset A from the lower edge upwardly toward the waist-line thereof, and thence with an edgewise bend, b, upon itself returning downwardly to said lower edge, a band or stripe, B', extending from the upper edge of the corset downwardly toward the waist-line, and thence with an edgewise bend, b', upon itself returning upwardly to said upper edge, the bent portions b and b' of said bands being located opposingly to each other above and below the waist-line, and a circular band or stripe, C, located at the waist-line between the opposed bent portions b and b' of the bands B and B'.
